UNITED STATES PATENT OFFICE

MAX KREHER, OF FREIBERG, GERMANY, ASSIGNOR TO CURT LUDWIG, OF ANNABERG, GERMANY

FLOATLESS CARBURETOR

Application filed March 12, 1929, Serial No. 346,369, and in Germany January 29, 1929.

This invention relates to a floatless carburetor, characterized in that it is a carburetor without throttle valve. The construction and the object of the arrangements will be hereinafter explained.

Two embodiments of the invention are illustrated by way of example in the accompanying drawings.

As however the difference between the two embodiments concerns only one single element, both embodiments will be described together.

Fig. 1 shows the improved carburetor in elevation.

Fig. 2 is a longitudinal section of Fig. 1.

Fig. 3 is a part section, and illustrates the second form of construction.

Fig. 4 shows in elevation the lever for operating the releasing device for the valve.

Fig. 5 shows in vertical section, partly in elevation the mushroom shaped valve or injection head.

Fig. 6 is a top plan view of Fig. 5.

Fig. 7 is a top plan view of the cup of the valve.

Fig. 8 shows in vertical section partly in elevation a modified construction of the valve needle.

Fig. 9 is a similar view as Fig. 8 showing a further modification of the valve needle.

The carburetor case is composed of two parts 1 and 2. The upper part 1 has a flange 3 at the top end by means of which the case is to be connected to the motor, the lower end being offset with regard to the lower part 2, whereby a shoulder 4 is formed. The lower part 2 comprises further a transverse plate 5 extended in downward direction by a hub 6 and in upward direction by a tubular extension 7. The transverse plate 5 is bored in longitudinal direction. A tubular extension 8 at the right side is internally threaded for connection to the fuel pipe and the horizontal bore 9 communicates with the vertical channel 10 which communicates with the central bore of the tubular extension 7. A calibrated plug 11 is mounted in the horizontal bore 9. The upper edge of the tubular extension 7 is bevelled in inward direction

and forms a seat 12. From the tubular extension 7 an air channel 13 extends into the open through the part 2 and in which a regulating element is arranged. To the lower end of the part 2 of the casing a fore-chamber 14 for the suction air is fixed by means of a screw 15 in the hub 6. The difference of the two forms of construction relates merely to this air chamber. 55

As shown in Fig. 1 the air chamber 14 has two admissions 16 through one of which hot air can be supplied which flows through a conduit heated by the exhaust pipe, or fresh air may be supplied also. In the latter case the pipe is removed and in each of 65 the two admissions 16 a seat is inserted to prevent access of foreign bodies.

Fig. 3 shows the other form of construction of the air chamber 14 designed only for fresh air. This chamber 14 is separated from part 2 of the casing by an air gap 17 closed by wire gauze. In part 2 of the case underneath the shoulder 4 a venturi 18 is inserted which is supported by a spiral spring 19 pressing the ring permanently 75 against the shoulder 4. The inner surface of venturi 18 is outwardly inclined at the upper portion in upward direction and at the lower portion in downward direction so that a burr or sharp edge 20 is formed. 86

The fuel valve or injection head is mushroom-shaped. The stem 21 is bored and has at its bottom portion 22 four longitudinal slots 23. The stem ends at the top end in a threaded neck 24. From the stem 21 radial arms 25 extend which carry on the outer ends a crown 26, from the lower surface of which a vertical flange 27 projects. The crown 26 carries a ring 28 of curved cross section and forms, together with this ring, 85 an annular chamber 29. The ring 28 has inwardly extending arms 30. A cap nut 32 screwed on the threaded neck 24 and having a central hole 31, rests upon the ends of the radial arms 30 and secures the ring in its position. In the radial arms 25 of stem 21 channels 33 are formed which end in the annular chamber 29. From the chamber 29 extend channels 34 in outward direction and further inwardly directed channels 35. In 100

the neck 24 of the stem 21 a bearing plate 36 for a ball 37 is mounted.

In the bottom portion 22 of the stem 21 a needle valve is mounted which consists of 5 the needle and of the head made in one piece and is permanently pressed downward by the action of a spiral spring 38.

Three forms of construction of the valve are illustrated.

10 In Figs. 1 and 5 the valve consists of a solid body 39. As shown in Fig. 8 the valve body 40 has a central bore stepped to form a seat 41. The bore is closed at the upper end by a nipple 42 having a central channel 43. In the walls above the seat 41 passages 44 are arranged. Near the lower end tap very narrow channels 45 are provided in the boring. The seat 41 carries a closing cone 46.

15 20 The construction shown in Fig. 9 is similar; only the channel 45 is omitted and a channel 47 extends through the point.

The mushroom-shaped valve or injection head is inserted into the tubular extension 7 25 so that the needle engages with the channel 10, this channel and also the horizontal bore 9 being constantly filled with benzine from the benzine reservoir. The needle carries the mushroom-shaped upper portion. Between this mushroom-shaped portion and the seat 12 a gap 48 remains and between the lower end of the valve and the bottom of the tubular extension 7 a hollow space 49 is left.

30 35 On a stationary shaft 50 a link 51 is keyed to which two rods are hingedly connected. The rod 52 is guided in an eye 53 and bears against the venturi 18. The other rod 54 is tubular and a rod 55 is telescoped in the same. A collar 56 of rod 55 can oscillate in the central hole 31 and carries the ball 37.

The operation when the valve 39 is used, is as follows:

40 45 The suction draft at the starting lifts the mushroom and through the same the needle so that the channel 10 is slightly opened and lets pass the quantity of benzine required for the starting. The benzine rises in the stem 21 and flows through the channels 33 50 into the annular chamber 29 and thence through the outflow channels 34 and 35. An air channel 13a terminates in the hollow space 49. When starting the air flows from the channel 13 through 13a into the hollow 55 space 49 and then into the hollow stem 21 along the same path as the benzine and forms a mixture with the benzine which passes off through the channels 34, 35. After the throttle valve has been further 60 opened the air from the forechamber 14 flows first around the cup and, as soon as the flange 27 of the valve has uncovered the passages 48, through the cup around the inner outflow channels. The benzine admission 65 is automatically increased according to

the increase of air admission in the desired relation. When the mushroom-shaped valve has been lifted to the highest position, the air and benzine supply is maximum.

The mushroom-shaped valve or injection head is automatically lifted by the suction draft but must be liberated by means of a lever 57 rotating the shaft 50 so that the rod 52 presses the venturi 18 upon this ring 19, the tubular rod 54 ascending and drawing along the telescoped rod 55 with the mushroom-shaped valve.

70 75 When one of the valve constructions shown in Figs. 8 and 9 is used, it is not necessary for the operator to release the mushroom valve in order to admit the fuel. The starting draft lifts through the channel 43 only the cone 46, the benzine rises through the channel 45 or 47 and through the passages 44 into the hollow stem 21. The 80 mushroom-shaped valve is lifted only at full speed, the operation being otherwise 85 similar to that described above.

The security against upsetting of the needle at mis-ignitions has further to be 90 mentioned. The shock from mis-ignition depresses the mushroom-shaped valve or injection head the distance of the gap 48 until the cup is bearing against the seat 12, this depression being rendered harmless for 95 the needle by the free space 49.

I claim:

1. An injection head for floatless carburetors, comprising in combination a hollow stem provided with slots, a head composed of radial arms, and a ring with outlets towards the inside and outside in the suction air current flowing not only around but also through said head.

100 2. An injector head as specified in claim 1, comprising in combination with the hollow stem a support with air feed adapted to carry said hollow stem and forming a mixing forechamber.

105 3. In an injector head as specified in claim 1, a flange adapted to first close and then open the path for the suction air.

110 4. An injector head as specified in claim 1, comprising in combination with the hollow stem a needle valve, and a bottom portion of said stem forming a seat for said needle valve.

In testimony whereof I affix my signature.
MAX KREHER.
